United States Patent Office.

J. NICOLAI, OF BOSTON, MASSACHUSETTS.

Letters Patent No. 71,045, dated November 19, 1867.

IMPROVED FOLDING CHAIR.

The Schedule referred to in these Letters Patent and making part of the same.

TO ALL WHOM IT MAY CONCERN:

Be it known that I, J. NICOLAI, of Boston, in the county of Suffolk, and State of Massachusetts, have invented certain new and useful Improvements in Folding Chairs; and I do hereby declare that the following is a full and exact description thereof, reference being had to the accompanying drawings, and to the letters of reference marked thereon.

The nature of my invention consists in so constructing and putting together the parts of a chair that the whole, when combined, shall constitute a strong, cheap, and convenient chair, capable of being folded into a very compact form.

To enable others skilled in the art to make and use my invention, I will proceed to describe its construction and use. In the drawings—

Figure 1 represents a perspective view of my chair open already for the occupant.

Figure 2 is an elevation of the chair as it appears when folded.

Figure 3 is a vertical section.

I construct my chair as follows: B B', fig. 1, form the back and two legs, and are framed together by means of a rung, N, and cross-bars O F, fig. 3. A A' are two pieces, forming the rear legs of a chair and part of the arms, being connected together by means of a rung, N', at the lower extremities, and a rung, L M, near the upper extremities. The parts A A' are connected to the parts B B' by pivots H H'. C C' represent the frame of the seat of the chair, and is hinged, as shown in fig. 1, to the parts B B', and being otherwise supported when the chair is open by the rung L M. D E and D' E' are two straps, connected as shown, which serve as arms and as tensions to keep the rear and front legs of the chair from spreading. In the drawing, I have omitted representing the upholstery, as unnecessary.

To fold my chair, I have simply to lift the seat upwards against the back of the chair, and draw the legs together, which will cause it to take the form shown in fig. 2.

Having thus described my invention, I will proceed to set forth my claim.

What I claim as my invention, and desire to secure by Letters Patent of the United States, is—

The combination of the legs A and B, pivoted at H, the handles D and D', the seat hinged at the rear end, and supported in front upon the rung M, substantially as described and for the purpose set forth.

J. NICOLAI.
